(57) **CLAIM**

The ornamental design for a screen corner assembly for a gutter guard system as shown and described.

DESCRIPTION

FIG. 1 is a top-left perspective view of a screen corner assembly for a gutter guard system;

FIG. 2 is a bottom-right perspective view of the screen corner assembly for a gutter guard system depicted in FIG. 1;

FIG. 3 is a top plan view of the screen corner assembly for a gutter guard system depicted in FIG. 1;

FIG. 4 is a bottom plan view of the screen corner assembly for a gutter guard system depicted in FIG. 1;

FIG. 5 is a front elevation view of the screen corner assembly for a gutter guard system depicted in FIG. 1;

FIG. 6 is a rear elevation view of the screen corner assembly for a gutter guard system depicted in FIG. 1;

FIG. 7 is a left-side elevation view of the screen corner assembly for a gutter guard system depicted in FIG. 1; and,

FIG. 8 is a right-side elevation view of the screen corner assembly for a gutter guard system depicted in FIG. 1.

1 Claim, 6 Drawing Sheets
